UNITED STATES PATENT OFFICE.

ARTHUR WILLIAM McCOMAS AND HENRY A. FITZHUGH, OF AUSTIN, TEX.

POR TABLE FAN AND OPERATING MACHINERY FOR SAME.

SPECIFICATION forming part of Letters Patent No. 337,848, dated March 16, 1886.

Application filed July 17, 1885. Serial No. 171,884. (No model.)

To all whom it may concern:

Be it known that we, ARTHUR WILLIAM McCOMAS and HENRY A. FITZHUGH, citizens of the United States, residing at Austin, in the 5 county of Travis and State of Texas, have invented certain new and useful Improvements in Portable Fans and Operating Machinery for same; and we do hereby declare the following to be a full, clear, and exact description 10 of the invention, such as will enable others skilled in the art to which it appertains to make and use the same.

Our present invention is an improvement in fans and mechanism for operating the same, 15 to be used for general purposes.

Our fan is fluted or corrugated, (as seen in transverse section,) its lines of corrugation radiating from a common point. By this peculiar formation we are enabled to concentrate 20 the surrounding air during its movement, and direct and carry it in a body back and forth with better effect than may be done by a fan having a plane surface, which allows the air to escape laterally before it has had its full effect 25 upon the objects which are intended to be reached. A heavy bead or bar follows the zigzag or corrugated outline of the bottom of the fan, and serves as a weight to keep it tending downward toward a position of rest. The 30 frame of the fan is made of metal covered with a durable fibrous or textile material.

The frame carrying our fan is supported upon standards provided with broad footings, which rest upon caster-wheels, by which the 35 fan may be readily moved from place to place. The standards carry a train of gear-wheels which multiply power and connect with levers, arms, and so forth, which, in an indirect manner, give a reciprocating movement to the 40 fan.

In the drawings, Figure 1 is a side elevation of our improved fan and driving mechanism, showing the several parts united and applied. Fig. 2 is a perspective view of our 45 fan and the mechanism immediately connected with it. Fig. 3 is a diagram exhibiting the movement of the fan when operated upon by the movement of the levers which impart motion to it.

50 Similar reference-letters indicate like parts in all of the figures.

Referring to the drawings, A A represent

the uprights or standards of the frame, provided with broad footings to form a base. These footings are provided with rollers or 55 caster-wheels upon which the structure rests, and by which it may be rendered easily portable.

At a proper point upon one side of the uprights A is a bracket, L, near the outer end 60 of which is pivoted a rocking lever, K. On one end of this rock-lever is an arm, N, which connects with the rod or pendulum F, which latter is pivoted upon a bar, B', at a point, Q, which bar is secured in the uprights 65 or standards A A.

The pendulum F, which is provided with a ball or weight, C, is intended to regulate and equalize, in the usual manner, the movement 70 of the operating mechanism for the fan.

Extending upward from the bar B', which serves as a pivot for the pendulum, is an arm, S, and to this arm is coupled a rod, U, which connects, in a manner hereinafter to be mentioned, with the fan.

A" is a bent bar, which is hinged to the standards A A, and extends outward in the form of a U, to support the fan. This bent arm is held in position by rods P, hinged to the standards at R, and coupled to said arm 80 A" by hinge and sliding joint M.

When desirable, the arm A" may be lowered or raised about its axis, and secured to position by clamping-screws in said joint M.

Sliding couplings X are provided upon the 85 arm A" and connected together by a bar, X', and upon this latter is hung by suspending- rods Y the fan Z, as shown.

A pitman, H, connects the rock-lever K and a crank, I, secured to a shaft journaled 90 upon the standards A A. Upon this shaft, to which is attached the crank I, is fixed also gear-wheel J, which connects with the main driving-shaft by wheel G, pinion C', wheel E, pinion D', and driving-wheel D.

The fan Z is of a fixed, corrugated, or zig-zag form, and is composed, as previously mentioned, of a metal frame covered with some suitable covering material.

E² is the ribbing, which conforms to the 100 sectional outline of the fan, and serves as a weight to steady the said fan in its movement and bring it to proper positions.

The operation of the fan may be described

as follows: The driving-wheel, with its teeth meshing with pinion D', imparts motion to the pendulum and arm S through wheel E, pinion C', wheel G, pinion J, crank I, pitman H, 5 rock-lever K, and arm N. Rod U has slide-joints T and V to connect arm S with an arm, W, fixed upon the bar X', and while the driving mechanism is in motion a rocking movement is imparted to said bar X' and the sus-
10 pending-hooks Y. When the arm W is moved out, the suspending-rods move toward x (see diagram, Fig. 3) and carry the top of the fan with them, and the bottom, being weighted, follows to give the fan perpendicular position.
15 A reverse movement of arm W carries the top of the fan toward z, and the lower portion, gravitating, gives the first serviceable sweep to the fan. This movement of the fan, which is indirect from the operating mechanism,
20 modifies to a considerable extent the wear and tear to the parts of the operating machinery.
The length of the arc of movement to the fan may be regulated and changes made by means of sliding couplings T and V, when ad-
25 justed upon arms S and W, and clamped to position by clamping-screws.
Having thus described our invention, what we claim as new, and desire to secure by Letters Patent, is—
30 1. In a fan to be operated by suitable driv-
ing mechanism, as set forth, the combination,
with the straight and rigid upper bar and the
zigzag or corrugated weighted lower bar, of
suitable radial connecting-ribs and covering
35 materials, substantially as set forth.

2. The combination, with the U-shaped hinged arm A", supporting-bars P, by which said arm may be held above or below a horizontal plane, the adjustable bar X', provided with sliding couplings X and suspending-rods 40 Y, of the bar B', uprights W and S, and rod U, by which said uprights W and S are adjustably connected, as and for the purpose set forth.

3. The combination, with the upright stan- 45 chions B, fixed upon a suitable base, hinged arm A", hinged supporting-bars P, by which said arm may be held above or below a horizontal plane, the adjustable bar X', provided with sliding couplings X, suspending-rods Y, bar 50 B', uprights W and S, and adjustably-con-
nected rod U, of fan Z, suspended upon said rods Y, all arranged as and for the purpose specified.

4. The combination, with the suspended fan, 55 supporting-arm A", and connecting-rod U, substantially as set forth, of the driving mech-
anism composed of rock-lever K, arm N, pend-
ulum F C, pitman H, crank I, and the train
of gear-wheels, all arranged substantially as 60
and for the purpose set forth.

In testimony whereof we affix our signa-
tures in presence of two witnesses.

ARTHUR WILLIAM McCOMAS.
HENRY A. FITZHUGH.
